(57) **CLAIM**

The ornamental design for a satchel, as shown and
described.

DESCRIPTION

FIG. 1 is a perspective view of the satchel showing my new
design;

FIG. 2 is a perspective view thereof from another angle;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view thereof, showing the satchel in
a closed configuration;

FIG. 10 is a perspective view thereof, showing the satchel in
a closed configuration from another angle; and,

FIG. 11 is a partial enlarged view of portion 11 in FIG. 1.
The dash-dash broken lines depict portions of the satchel
that form no part of the claimed design. The short-dash
long-dash lines in FIGS. 1 and 11 represent the bounds of the
enlargement taken from FIG. 1 and forms no part of the
claimed design.

The satchel is shown with a symbolic break in its length. The
appearance of any portion of the article between the break
line forms no part of the claimed design.
